UNITED STATES PATENT OFFICE.

LEWIS COLIN GRANT, OF NEWCASTLE-UPON-TYNE, ENGLAND, ASSIGNOR TO ELECTRICAL IMPROVEMENTS LIMITED, OF NEWCASTLE-UPON-TYNE, ENGLAND, A COMPANY OF GREAT BRITAIN.

LIGHTNING OR SURGE ARRESTER.

Application filed October 5, 1925. Serial No. 60,592.

This invention relates to lightning or surge arresters and has particular reference to arresters intended primarily to deal with traveling and standing waves of high frequency on electric transmission lines such as waves caused by lightning or surges which may be due to an induced line charge, an arcing fault or any phenomena usually classed as lightning and transient line surges.

Many arresters have been proposed for this purpose and in general, they have been intended to remove the charge from the line by a discharge to earth.

The primary object of the present invention is to provide a simple and reliable arrester which will dissipate the energy due to a surge without having to earth the line, and for this purpose the arrester is so arranged that the energy of a surge is transmitted electromagnetically from a primary connected in series with or forming part of the line to a secondary whence it is dissipated in the form of heat.

A further object of the invention is to provide a convenient and compact practical arrangement of the primary and secondary which form the essential elements of the arrester.

Further objects of the invention will be apparent from the following description of the accompanying drawings and from the appended claims.

The accompanying drawings show one practical construction of arrester according to the invention. In these drawings,

Figure 1 is a longitudinal section, a part being broken away,

Figure 2 shows on a smaller scale an external view of the arrester shown in Figure 1 provided with insulated terminals for connection to the line.

In the construction of Figure 1 the primary A of the transformer constituting the arrester is composed of four conductors A¹ A² A³ A⁴ of square-section copper connected in parallel with one another. These conductors are wound one upon the other with consecutive turns of each winding close together so that the whole primary is in the form of a compact tubular structure. The four windings are arranged to cross over, one another near the middle of the primary (as indicated at B), the outer winding on

one side becoming the inner winding on the other side and so on. This arrangement enables the resistances and impedances of the four windings to be made equal to one another. Heavy paper insulation C (for example, capable of withstanding 40,000 volts) is provided between the superimposed windings and between adjacent turns of the windings.

The secondary consists of two tubes E, F disposed respectively around and within the primary A, the two tubes being electrically connected together by end plates E². Tubular paper insulation D arranged in one or more layers is provided to insulate the primary A from the tubes E, F and the end plates E², this insulation being passed through holes in the end plates (as shown at D¹) to allow of the external connection of the primary.

The arrangement is such that there is a very close coupling between primary and secondary with adequate insulation, whilst the whole structure is mechanically very strong and considerable resistance is offered against circumferential expansion of the primary.

The energy of a surge in the line (to which the primary is connected in series) is transferred electromagnetically from the primary A to the secondary (tubes E and F) which acts to convert this energy into the form of heat and to dissipate the heat by radiation from the outer surface of the tube E and the inner surface of the tube F. For this purpose the tubes E and F are constructed of a material which has high specific heat, high thermal conductivity, high melting point and comparatively high ohmic resistance. Cast iron and other forms of iron comply to a large extent with these conditions, and a very suitable material is a recently developed form of iron which has an extremely high specific resistance (of the order of 140 micro-ohms per centimetre cube) and has also the further important advantage of being substantially non-magnetic.

The tube E forms the outer casing of the arrester and is provided with flanges E¹ to receive end plates E² (see Figure 2) which carry insulated terminals E³ by means of which the primary is connected in series with the line. Other means may be em-

ployed for the connection of the arrester to the line or apparatus to be protected.

Owing to the fact that the secondary is high aperiodic, it is possible to abstract so much energy from the surge that the building-up of potential is prevented and no disruptive discharge takes place. Under normal working conditions, as the line frequency is relatively very low, the amount of energy transferred to the secondary is negligible.

What I claim as my invention and desire to secure by Letters Patent is:—

1. A lightning or surge arrester in the form of a transformer comprising a secondary which consists of two concentric tubes electrically connected together, and a primary winding disposed in the annular space between the two tubes, the secondary acting to 20 dissipate in the form of heat energy which it derives from a surge in the primary.

2. A lightning or surge arrester comprising an inductive winding which is formed of a group of conductors connected in parallel with one another and in series with the line and which constitutes the primary of a transformer, and a secondary part of which surrounds the primary whilst part is disposed within the primary, such secondary acting to dissipate in the form of heat energy which it derives from a surge in the primary.

3. A lightning or surge arrester in the form of a transformer comprising a secondary which consists of two concentric tubes electrically connected together, and a prima-

ry which is disposed in the annular space between the two tubes and consists of a group of superimposed windings connected in parallel with one another, the secondary acting 40 to dissipate in the form of heat energy which it derives from a surge in the primary.

4. A lightning or surge arrester in the form of a transformer comprising a secondary which consists of two concentric tubes 45 electrically connected together, and a primary winding disposed in the annular space between the two tubes and formed of insulated square-section conductor, the secondary acting to dissipate in the form of heat 50 energy which it derives from a surge in the primary.

5. A lightning or surge arrester in the form of a transformer comprising a secondary which consists of two concentric tubes 55 electrically connected together, a primary which consists of a group of superimposed windings connected in parallel with one another each winding being formed of insulated square-section conductor with its adjacent turns wound closely together so that the whole primary is in the form of a compact tubular structure disposed within the annular space between the two tubes, and two tubular insulating layers disposed respectively between the primary and the two tubes, the secondary acting to dissipate in the form of heat energy which it derives 60 from a surge in the primary.

In testimony whereof I have signed my name to this specification.

LEWIS COLIN GRANT.
